PILE CUTTING MECHANISM

Robert Adamson, Mystic, Conn.

Application September 29, 1953, Serial No. 382,995

3 Claims. (Cl. 139—43)

1

The present invention relates to pile cutting mechanism for velvet and plush weaving looms wherein the pile cutting knife is actuated by solenoids.

In a known form of plush weaving loom the pile cutting knife is mounted on a carrier which is reciprocated mechanically between guideways forming part of the loom bench. It is contemplated that the present invention may conveniently be applied to said conventional type of loom by removing the mechanical knife operating mechanism and substituting therefor the devices hereinafter described.

One object of the invention, whether applied in place of conventional or other mechanical devices in a known type of loom or incorporated in a new loom, has been to simplify the pile cutting mechanism and render it safer and more reliable in operation.

A further object of the invention has been to provide a pile cutting knife control mechanism producing simpler and more effective actuation of the knife and providing dependable stop means by which cutting movement of the knife is stopped effectively and with minimum impact and recoil. Thus, at the end of each cutting stroke the knife is properly positioned to receive the next thrust of the driving means.

Knife operating mechanism according to the present invention comprises in general a reciprocable knife carrier, a solenoid on each end of the bench which provides the path of movement of said carrier, switch means in the circuits of said solenoids, and actuating means including timing mechanism arranged and adapted to operate said switch means whereby said solenoids are alternately energized and deenergized. Furthermore, said apparatus includes shock absorbing and damping devices which reduce the velocity of the carrier near the end of its pile cutting run and limit the extent and violence of recoil resulting from impact of the carrier upon the fixed carrier stops.

A preferred embodiment of the invention is more fully described in the following specification as illustrated in the appended drawings wherein:

Figure 1 is a view in perspective showing diagrammatically the principal parts of a usual velvet or plush loom including a conventional form of bench and a mechanically actuated pile cutting knife arranged in operative relation thereto;

Figure 2 is a diagram showing in perspective a pile cutting knife carrier with the actuating and control devices of the present invention applied thereto;

2

Figure 3, a diagram showing partly in elevation various of the parts shown in Figure 2;

Figure 3A, a transverse section in the line T—T of Figure 3;

5 Figure 4, a diagrammatical fragmentary plan view, on enlarged scale, showing solenoid parts in relation to the knife carrier at one end of the loom bench; and

10 Figure 5, an enlarged fragmentary view in perspective illustrating details of the solenoid mounting and the knife carrier stopping and damping means at one end of the loom bench.

Referring to the drawings, the conventional type of loom illustrated in Figure 1 provides mechanical pile cutting knife actuating means including at each side of the loom crank A on the loom power shaft which imparts reciprocating endwise movement to rod B thus rocking the gear segment C to rotate drum D. The rope E wound on drum D is thus alternately pulled and released so that the knife H is reciprocated across bench G in synchronism with the loom shuttles, to cut the pile threads exposed thereto in a conventional manner.

20 25 30 35 40 45 50 55 As shown in Figure 2, the mechanism embodying the invention is indicated generally in full lines and in operative relation to a conventional form of loom bench G, knife H and loom fabric in process shown in dotted lines. The knife carrier K is conveniently in the form of a slidable rod or bar Figures 4 and 5 which slides endwise in a groove on the top of bench G formed by parallel guides J secured thereto. As seen in Figure 5, the knife H is secured to end portions of a pair of brackets 21 which are mounted in spaced relation on carrier K and extend laterally therefrom.

Said carrier K is actuated by solenoid devices 1 and 2 conveniently mounted on shelves 3 and 4, respectively, at opposite ends of bench G, as shown more clearly in Figure 2. The cam 5 on power shaft 20 of the loom actuates a single pole double throw switch 6 to alternately open and close the circuits of said solenoids during each revolution of said shaft 20 and in synchronism with reciprocating movements of the loom shuttles. A power line 8 supplies current to said solenoid circuits through a control panel 7 which advantageously includes a hand operated switch, not shown.

The arrangement of the knife carrier K in relation to the solenoids 1 and 2 is such that the plungers 9 and 10 thereof moving against resistance of the biasing or retracting springs 16 strike or thrust the knife carrier alternately in opposite directions to drive it across bench G, thus at each

run bringing knife H into pile cutting operation against and across the pile threads as the woven fabric advances in the weaving process.

As shown in Figure 5, the brackets 21 on knife carrier K are provided with transversely disposed upwardly extending ridges 11 substantially V-shaped in cross-section and presenting longitudinally extending oblique faces which cooperate with the substantially cylindrical or rounded surface portions of the free end of spring 12 in a manner and for purposes hereinafter set forth. The opposite end of said spring 12 is secured to guide bar J in such position that, when knife carrier K near the end of its pile cutting run, the leading oblique face of ridge 11 engages and then rides under the rounded end of said spring 12 which in effect thus acts in part as a shock absorber to materially reduce the velocity of carrier K just before its leading end comes against the fixed stop plate 13. This also brings the rounded end or surface of said spring 12 into position to be engaged by the other or trailing oblique face of ridge 11 and thus to limit or reduce the extent of rebound or recoil of said carrier K when its leading end strikes stop 13. Thus, in operation, said spring 12 and said ridge 11 cooperate both to reduce the velocity of carrier K near the end of its pile cutting run and to limit recoil thereof after its impact upon stop 13.

As shown more clearly in Figure 5, the plunger 10 of solenoid 2 (and this applies as well to plunger 9 of solenoid 1 at the opposite end of bench G) carries at its inner end a striking piece or plate 14 having a depending portion which, when solenoid 2 is energized with the closing of switch 6 by cam 5 against resistance of spring 6A, strikes carrier K thus forcing it along with knife H across the bench G toward plunger 9 of solenoid 1. When the latter is energized with the next actuation of switch 6 by said spring 6A, after release from cam 5, Figure 3, a similar striking piece on plunger 9 impels carrier K back to its initial position and in readiness for the next run in the opposite direction.

The loom parts are so synchronized that each of said solenoids 1 and 2 is deenergized when the other is energized. Also, as soon as solenoid 2, for example, is inert, plunger 10 is moved to its retracted position by said biasing springs 16 each of which has one end attached to a plate 15 carried at the forward end of said plunger 10 and the other end anchored to a bracket 17 fixed to shelf 4.

Endwise pile cutting movement of carrier K, Figure 5, towards plunger 10 produced as above described is ultimately stopped by said stop plate 13 which, as shown, is of less thickness than the bars or plates of carrier K, and guide bars J, thus permitting the lower end of striking plate 14 to move between said guides J and against an upper portion of the opposed end face of said carrier K when plunger 10 is actuated by the energization of the circuit of solenoid 2.

The impact of carrier K at the end of its pile cutting run against stop plate 13 would in the absence of cushioning means, produce undesirable recoil or rebound likely to impair or prevent

the next pile cutting operation of said carrier K. However, as carrier K approaches its end position, said ridge 11 slides under the end of spring 12 which, in yieldingly resisting displacement upwardly absorbs a portion of the energy and reduces the velocity of the moving parts and thus the extent of recoil as said carrier K strikes said stop plate 13. Furthermore, spring 12 tends to damp chattering or vibrations produced by said impact, in part by reason of the friction between spacing blocks 22 on the under side of said brackets as said blocks bear against adjacent top surface portions of guide bars J with the downward pressure exerted by the face end of spring 12 on said brackets 21 and blocks 22.

What I claim is:

1. In apparatus for actuating and controlling operation of the pile cutting mechanism in a loom of the velvet or plush weaving type, the combination of a pile cutting knife carrier mounted for longitudinal reciprocating movement along a bench which extends across the path of the pile threads of a double fabric as the latter is advanced through the loom, a carrier actuating assembly at each end of said bench including a solenoid having a plunger normally spring biased in retracted position when the solenoid is de-energized and arranged with one end opposite an end of said knife carrier, and means for energizing each of said solenoids alternately with the other including a single pole double throw switch in circuit with said solenoids and normally spring biased to close the circuit of one of them, and means for periodically actuating said switch to open said circuit and close the circuit of the other of said solenoids.

2. In apparatus for actuating and controlling operation of the pile cutting mechanism in a loom of the velvet or plush weaving type, the combination of a pile cutting knife carrier mounted for longitudinal reciprocating movement along a bench which extends across the path of the pile threads of a double fabric as the latter is advanced through the loom, a carrier actuating assembly at each end of said bench, and carrier stopping means at each end of said bench including a fixed stop positioned in the path of movement of the carrier to limit the extent thereof, a buffer spring having a free rounded end at one side of said path of movement of the carrier, and a projection extending from said carrier in position to engage and ride under said rounded end against resistance of said spring when said carrier is nearing its terminal position and to be engaged by said rounded end to restrain said carrier against recoil after the latter has reached terminal position against said fixed stop.

3. Apparatus according to claim 1, and including a fixed stop positioned to limit and stop the pile cutting movement of said carrier, shock absorbing means positioned to reduce the velocity of said carrier before impact thereof on said stop, and damping means positioned to reduce recoil after impact of said carrier on said stop.
